UNITED STATES PATENT OFFICE

WILLIAM N. CRAMER, OF CHICAGO, ILLINOIS

ROOFING

Application filed May 31, 1930. Serial No. 458,207.

This invention relates to roofing, and particularly to shingle roofing applied to simulate thatched roofs. The invention is particularly concerned with the production of a roll effect at the eave and gable edges of the roof which gives the appearance of thickness and the stubble effect which are characteristic of a thatched roof.

In order to provide such a roll effect I 10 build up a framework of the desired configuration and apply thereto successive rows of relatively short stout shingles having relatively thick butts. Such shingles lend themselves to the coverage of sharply arcuate surfaces as will be hereinafter explained.

The invention will be readily understood from the following description of preferred embodiments taken in conjunction with the accompanying drawings, in which—

20 Figure 1 is a diagrammatic illustration of a house provided with a shingled roof simulating thatch;

Fig. 2 is a perspective view of a wooden shingle suitable for the formation of a roll;

25 Fig. 3 is a similar view of a shingle shaped clay tile provided with nail holes, which may be used according to the invention;

Fig. 4 is a similar view of a composition shingle provided with metal armor to facilitate satisfactory nailing;

Fig. 5 is a sectional view of an eave roll;

Fig. 6 is a plan view of a gable or dormer roll; and

35 Fig. 7 is a sectional view of the same on the line 7 of Fig. 6.

Referring to the drawings, the main portion of the roof is covered with full sized shingles 10, applied in the ordinary way upon sheeting 11, which is secured to the rafters 12. As shown in Fig. 6 the lower exposed transverse edges of the shingles 10 extend irregularly so that the successive rows of these shingles present transverse lines upon the roof which are somewhat undulatory and simulate the appearance of a thatched roof. These wavy lines are produced as by an irregular laying of shingles having a rectangular shape or non-parallel side edges, or by a straight laying

of shingles whose butt edges are curved or obliquely disposed in relation to the side edges, this latter construction being shown in the drawings.

Around the edges of such a roof I produce 55 a roll 13. To support the roll I provide a framework having the desired exterior configuration. Thus, with an eave roll, as shown in Fig. 5, the rafters 12 project beyond the building line and are cut to the 60 desired arcuate configuration. Additional supporting members, for example, the outlooks 14, may be provided. The curved ends of the rafters are provided with a sheeting 15, which preferably comprises a plurality 65 of relatively narrow boards. If desired, a soffit 16 may be secured to the outlooks 14.

In building the roof successive rows of relatively short stout shingles 17 are applied upon the sheeting 15 as shown in Fig. 5. 70 The shingles 17 may vary in length and butt thickness within wide limits. I have used shingles from two inches long having a butt thickness of three-eighths of an inch, up to shingles six inches in length with 75 one-half inch butts. I have found that each shingle size can readily be adapted to cover surfaces of widely differing curvature. Thus, with shingles of five inch length and one-half inch butt thickness, exposure of the 80 butt ends of three-fourths inch will adapt the shingle to cover a surface of eight inches radius. An exposure of one and one-fourth inches is suitable for a surface of ten inches radius while an exposure of one and one-half inches adapts the shingle to a surface of thirteen inches radius. It will readily be understood that the larger and smaller size shingles possess a similar adaptability.

After the sheeting 15 is covered the large 85 shingles 10 are applied in the ordinary way. The butt edges of the shingles 17 are preferably and slightly irregularly waved as shown in Figs. 2, 3 and 4. It will readily be understood that this waviness, together 90 with the large number of lines provided by the numerous shingles 17, imparts an appearance of thickness and also a stubble effect characteristic of thatched roofs. It will be readily understood that the roll may take 95

100

forms other than that shown. For example, the framework may be readily built so as to bring the roll back to the building line, omitting the soffit 16.

5 In making a gable roll as shown in Figs. 6 and 7, I provide overhanging outlooks 18 which may be secured to the outermost rafters 12 or other suitable parts of the structure. The outermost parts of the out-
10 looks 18 are curved to support the sheeting 19. As shown in Fig. 7, the roll terminates adjacent a barge board 20. A soffit 21 is secured to the outlooks 18 between the barge board 20 and facia board 22. It will readily
15 be understood that the barge board 20, soffit 21 and facia board 22 may be omitted and the roll continued back to the building line. It will readily be understood that the shingles 17 are applied in the same manner as
20 described in connection with the eave roll. With this roll the shingles 10 and 17 are at right angles to each other. The shingles 10, which are superimposed upon the upper-
25 most row of shingles 17, are trimmed obliquely, as shown in Fig. 7, to rest snugly thereon.

The shingles may be of any desired material. Thus, they may be of wood, as shown in Fig. 2, or of burnt clay, as shown in Fig. 3. In this case it is preferred to provide
30 nail holes 23. Composition shingles, such as are shown in Fig. 4, may also be employed. In order to facilitate secure nailing, it is preferred to apply a bent metal plate
35 24 upon the apex of the shingle. The metal plate may suitably have struck up triangular portions 25, which are adapted to penetrate into the shingle and hold the plate 24 in position. Such a plate may be employed
40 with wood and other shingles, if desired, but is ordinarily not necessary.

Although the invention has been disclosed in connection with the details of specific em-
45 bodiments thereof, it must be understood that the invention is not intended to be limited to such details except insofar as set forth in the accompanying claims.

I claim:

- 50 1. In combination, a shingled roof simulating the effect of thatch, a frame work at the edge thereof defining a roll and relatively short stout shingles applied to the roll with a small portion of the butt end exposed to simulate the stubble effect of thatch.
- 55 2. In combination, a framework at the edge of a roof defining a roll, and relatively short shingle having relatively stout butts applied thereto so as to expose small portions of the butt ends and simulate the stub-
60 ble effect of thatch.
- 65 3. In combination, a shingled roof simulating the effect of thatch, a framework at the edge thereof defining a roll and relatively short stout shingles having wavy butt edges applied to the roll with a small por-

tion of the butt end exposed to simulate the stubble effect of thatch.

4. In combination, a framework at the edge of a roof defining a roll, and relatively short shingles having wavy butt edges and having relatively stout butts applied thereto so as to expose small portions of the butt ends and simulate the stubble effect of thatch.

5 In testimony whereof I have hereunto set
my hand this 27 day of May, 1930.

WILLIAM N. CRAMER.
